(57) **CLAIM**

The ornamental design for a label, as shown and described.

DESCRIPTION

The patent or application file contains at least one drawing executed in color. Copies of this patent with color drawings will be provided by the Office upon request and payment of the necessary fee.

FIG. 1 is a front, top, right perspective view of the first embodiment of a label shown in an environment of use;

FIG. 2 is a rear view thereof;

FIG. 3 is a front view thereof;

FIG. 4 is a left side view thereof;

FIG. 5 is right side view thereof;

FIG. 6 is a top plan view thereof; and

FIG. 7 is a bottom plan view thereof;

FIG. 8 is a front, top, right perspective view of the second embodiment of a label shown in an environment of use;

FIG. 9 is a rear view thereof;

FIG. 10 is a front view thereof;

FIG. 11 is a left side view thereof;

FIG. 12 is right side view thereof;

FIG. 13 is a top plan view thereof; and

FIG. 14 is a bottom plan view thereof;

FIG. 15 is a front, top, right perspective view of the third embodiment of a label shown in an environment of use;

FIG. 16 is a rear view thereof;

FIG. 17 is a front view thereof;

FIG. 18 is a left side view thereof;

FIG. 19 is right side view thereof;

FIG. 20 is a top plan view thereof; and

(Continued)

FIG. 21 is a bottom plan view thereof;
 FIG. 22 is a front, top, right perspective view of the fourth embodiment of a label shown in an environment of use;
 FIG. 23 is a rear view thereof;
 FIG. 24 is a front view thereof;
 FIG. 25 is a left side view thereof;
 FIG. 26 is right side view thereof;
 FIG. 27 is a top plan view thereof; and
 FIG. 28 is a bottom plan view thereof;
 FIG. 29 is a front, top, right perspective view of the fifth embodiment of a label shown in an environment of use;
 FIG. 30 is a rear view thereof;
 FIG. 31 is a front view thereof;
 FIG. 32 is a left side view thereof;
 FIG. 33 is right side view thereof;
 FIG. 34 is a top plan view thereof; and
 FIG. 35 is a bottom plan view thereof;
 FIG. 36 is a front, top, right perspective view of the sixth embodiment of a label shown in an environment of use;
 FIG. 37 is a rear view thereof;
 FIG. 38 is a front view thereof;
 FIG. 39 is a left side view thereof;
 FIG. 40 is right side view thereof;
 FIG. 41 is a top plan view thereof; and
 FIG. 42 is a bottom plan view thereof;
 FIG. 43 is a front, top, right perspective view of the seventh embodiment of the label shown in an environment of use;
 FIG. 44 is a rear view thereof;
 FIG. 45 is a front view thereof;
 FIG. 46 is a left side view thereof;
 FIG. 47 is right side view thereof;
 FIG. 48 is a top plan view thereof; and,
 FIG. 49 is a bottom plan view thereof.

The autoinjector shown in broken lines shows the environment and does not form part of the claimed design. All other broken lines show portions of the label that form no part of the claimed design.

The greyscale shading in FIGS. 1 and 3 represents a contrast in appearance.
